(57) **CLAIM**

The ornamental design for a drone with case assembly, as shown and described.

DESCRIPTION

FIG. 1 is a perspective view of a drone with case assembly showing my new design;

FIG. 2 is a perspective view of a drone with case assembly, with drone component removed;

FIG. 3 is a perspective view of the case component thereof;

FIG. 4 is a rear perspective view of view of FIG. 3;

FIG. 5 is a front view of view of FIG. 3;

FIG. 6 is a back view of view of FIG. 3;

FIG. 7 is a left side view of view of FIG. 3;

FIG. 8 is a right side view of view of FIG. 3;

FIG. 9 is a top view of view of FIG. 3;

FIG. 10 is a bottom view of view of FIG. 3;

FIG. 11 is a perspective view of the drone component thereof;

FIG. 12 is a front view of view of FIG. 11;

FIG. 13 is a back view of view of FIG. 11;

FIG. 14 is a left side view of view of FIG. 11;

FIG. 15 is a right side view of view of FIG. 11;

FIG. 16 is a top view of view of FIG. 11;

FIG. 17 is a bottom view of view of FIG. 11;

FIG. 18 is a perspective view of an alternate configuration of the drone component of FIG. 11; and,

FIG. 19 is an exploded perspective view of the drone component of FIG. 11.

The broken lines shown in the drawings depict portions of the drone with case assembly that form no part of the claimed design.
